(57) CLAIM

The ornamental design for packaging with surface ornamentation, as shown and described.

DESCRIPTION

FIG. 1 is a front view of packaging with surface ornamentation showing a first embodiment of our new design; and, FIG. 2 is a front view of packaging with surface ornamentation showing a second embodiment of our new design. The dot-dash broken line defines a boundary of the claimed design and form no part of the claimed design. The dash-dash broken lines represent portions of the design that form no part of the claimed design.

1 Claim, 2 Drawing Sheets

FIG. 2
